UNITED STATES PATENT OFFICE.

THOMAS JOHNSON, OF LOS ANGELES, CALIFORNIA.

MEMORANDA HOLDER FOR HATS.

Application filed July 26, 1926. Serial No. 125,066.

This invention relates to a memoranda holder adapted for use within the crown of a hat or cap to be accessible for instantaneous use on emergencies. It is very common for 5 people to insert in the crown of their head-gear notes or other memoranda containing data for future use. In removing the hat however the papers are liable to be lost or blown away creating a tremendous amount 10 of trouble.

My invention is designed to provide a holder in which the memoranda may be securely stored and readily abstracted when required; the device serving this function is 15 an elastic tempered steel wire or ribbon of sufficient length to be bent into an arc and supported in proper alinement on the inside crown of a hat or cap. At its middle portion is mounted a clip with jaws adapted to 20 be brought snugly together to clamp one or more notes of papers containing the memoranda.

The invention therefore essentially comprises a holder to retain memoranda and 25 from which they may be readily removed, adapted for ready insertion within the crown of a hat and stably supported therein. It comprises other more specific features the 30 nature of which will be hereinafter more fully set forth in the present specification and the scope of which will be definitely indicated in the accompanying claims.

In the drawing illustrating an embodiment of my invention as applied to a cap 35 type of headgear.

Figure 1 shows in elevation the application of my improved holder to the inside of the crown of a cap.

Figure 2 shows the elastic sides of the device sprung together ready for insertion in 40 the crown of a hat,

Figure 3 shows in section the clip I prefer to employ, and

Figure 4 is a section on the plane 4—4 of 45 Figure 2 looking in the direction of the arrows showing an effective gripping clamp for my holder.

Referring now in detail to the drawing 1—1^a represent two lengths of tempered steel 50 wire curled at their free ends to ring form and lying in a plane axially of the wire as indicated at 2—2^a. The wires are twisted together as shown at 3 by a number of turns to provide a stiff joint and soldered in the 55 fold, as at 5, of a bent metallic strip of thin sheet metal the jaws of which are brought

into parallelism as at 6. The outer ends of the jaws are bent or curved at an angle, as indicated at 7, to afford a holder to admit of ready insertion of paper memoranda, and 60 near the curved edge is a struck up portion of the metal strip at several transverse points as indicated at 8, to provide symmetrically related dents which may indent and grip the memoranda. At an intermediate portion of 65 the holder is a fixed pin 9 securely attached to one of the jaws as by soldering, its screw-threaded end extending through an opening in one free jaw. A wing nut 10 engages the threaded portion of the screw to compress a 70 short helical spring 11 and afford an elastic adjustment for the jaws to admit different numbers of folded papers. The clamp 6 may with advantage be provided with enameled or embossed information as to the maker of 75 the hats containing the device.

It will thus be seen that my device is an exceedingly simple form of memoranda-holder, is readily applied and is adapted to maintain its position in stable parallelism 80 with the crown of the hat in which it is inserted and to securely afford storage capacity for temporary memoranda for the wearer of the cap.

Having thus described my invention, what 85 I claim as new and desire to secure by Letters Patent is:

1. A memoranda holder for a hat or cap comprising a straight thin elastic wire offset at its ends to hold it in alinement when applied in the crown of a hat and adapted when flexed to nest snugly within said crown, and a memoranda clamp with indented jaws fixed midway the ends of the wire to securely retain temporary memoranda.

2. A spring holder for memoranda adapted for insertion in a hat or cap comprising an elastic wire spring conforming to its inside crown, said wire being composed of two lengths twisted together to form a unit and an adjustable clamp fixed between its ends to secure the memoranda for emergency use.

3. A memoranda holder for a hat comprising a spring to nest elastically inside the crown of the hat, and a clamp for holding a plurality of memoranda papers connected with the spring disposed in a horizontal plane.

In testimony whereof I affix my signature.

THOMAS JOHNSON.
